REVERBERATIONS MODULATOR

Maurice Parisier, New York, N. Y.

Application January 7, 1944, Serial No. 517,321

10 Claims. (Cl. 179—1)

1

My invention relates to sound conditioning for radio transmission and has particular reference to sound conditioning by means of acoustic reverberation chambers in which the sound is electrically reproduced, conditioned, and further transmitted for broadcasting or recording.

It is well known fact that quality of sound such as music depends to a considerable extent on the particular properties of the space, for instance, a hall in which the sound is produced. The sound is repeatedly reflected from the walls, producing a more or less lasting effect of reverberation which affects the characteristics of the sound.

For obtaining the best acoustic results, music halls are usually specially designed to produce a uniform pleasing effect of reverberation (without objectionable echo, however).

It has been found, however, that the particular type of a confined space, such as a hall, while it may be very effective for certain kinds of sound, for instance, for violins or chamber music, may be unsatisfactory for other kinds of sound, such as produced by wind instrument, organ, singing, etc.

The reverberation effect depends on the physical dimensions of the confined space or hall, and to a considerable extent, on the surface of its walls, being different for smooth and rough surfaces, metal or wood, etc. Fabric (such as curtains) also considerably change the acoustic properties.

Reverberation effect is produced when a standing wave of sound is obtained in a confined space. When the sound is stopped, each individual mode of vibration will decay exponentially, and the combined effect of the reverberation may be expressed by the formula:

$$T = .00161 V/a$$

where V is volume of the room in cubic centimeters, a is a total room absorption = $(A'a' + A2a2 + \dots)$, A' , $A2$ being areas in square centimeters, having coefficients of absorption a' , $a2$, etc.

It has been found that a hall, built to obtain the best results for one particular type of sounds, may not be satisfactory for other sounds. A hall, suitable for sounds of low frequencies, may be entirely unsatisfactory for sounds of high frequencies. For the best results in the sound transmission by radio, it is necessary therefore to find means to change the reverberation properties of the room in accordance with the variations in the types of sound.

Proper control of reverberation is particularly

2

important in radio industry, for producing and recording music, speech, singing, etc., modulating the sound to suit particular requirements, so as to produce natural and most pleasing effects.

5 My invention has for its object to provide means and method of sound transmission whereby the reverberation effect is produced artificially, by means of a chamber in which the sound is reproduced electrically and retransmitted also electrically after it has been modified acoustically in the chamber. The chamber or enclosure is so constructed that its acoustic and reverberation properties can be rapidly changed at will, even during transmission of the sound. The chamber 10 for this purpose is provided with movable or collapsible walls which can be operated at a distance, by an electric motor, for instance, for causing the walls to collapse or to expand for varying the volume of the enclosure. For varying the other factor of the reverberation, i. e. sound-reflecting properties of the walls, the walls are made replaceable, operated by an electric motor, for instance, at a distance, so that one particular set of walls can be quickly replaced by another set, 15 having different kind of surface. A plurality of telescopic walls may be provided for this purpose or, preferably, the walls may be made of a suitable flexible material, such as fabric, plastic, etc., mounted on rolls from which it can be stretched along the sides of the chamber. Different portions of the flexible material may have different finish or may be even made of different materials.

I have found that for the purpose of imparting particular acoustic properties to the sound by 20 means of an adjustable acoustic reverberation chamber forming a part of a sound transmission system, such a chamber may be of relatively small dimensions.

With proper adjustment, it is possible to obtain 25 with such a small chamber the effect of the sound as produced in a large concert hall, in an open space, etc.

A single artificial reverberation chamber may 30 not be satisfactory, however, for transmitting mixed sounds in which sounds of widely different frequencies are used as, for instance, in the orchestral music, operas, singing, etc. Another object of my invention is, therefore, to provide means for independent conditioning of the sounds 35 of different frequencies. I transmit for this purpose by electrical means through a series of acoustic reverberation chambers, each chamber being adapted to receive electric impulses corresponding to a particular band of frequencies. Each chamber is adjusted for producing the de-

sired acoustic reverberation effect for the particular band of frequencies, and the thereby conditioned sound is reconverted into electric impulses for further transmission or for recording. Various special acoustic effects may be obtained thereby.

Another object of my invention is to modify individually the volumes of the different bands of sound frequencies and to recombine these bands into a single transmission channel for obtaining the desired final acoustic effect.

For certain purposes it may be desirable to separate the sound into two main channels for transmission, one portion of the sound being directly transmitted through regular microphones and amplifiers, the other portion being separated into different bands of frequency, each band being then separately conditioned in a corresponding reverberation chamber. The two portions are then recombined, means being provided to adjust the volume or amount of energy in each portion (and in each band) prior to their being combined together. The first portion, however, may be also divided into bands.

My invention is more fully described in the accompanying specification and drawings in which—

Fig. 1 is a sectional elevational view of my sound conditioning or reverberating chamber or enclosure;

Fig. 2 is a vertical sectional view of the same taken on the line 2—2 of Fig. 1;

Fig. 3 is a sectional elevational view of a modified chamber;

Fig. 4 is a diagram of connections of a radio transmission of sounds in which a series of my sound conditioning chambers is employed;

Fig. 5 is a fractional diagrammatic view of one group of reverberation chambers; and

Figs. 6 and 7 are diagrammatic views of modified acoustic chambers.

My reverberation chamber or enclosure 1 for sound conditioning, as shown in Figs. 1 and 2, in one of its practical embodiments, consists of a frame, preferably of a rectangular form, made of longitudinal bars 2, attached at the ends to end walls 3, 4. These walls are stationary in the present instance and carry electrosonic conversion means, the wall 3 supporting a loud speaker 6 of an ordinary suitable type, and the wall 4 supporting a microphone 7, also of a suitable ordinary type. The frame may be of relatively small dimensions. Brackets 8, 9, 10, 11 are mounted at the ends of the frame for shafts 12, 13, 14, 15 at one end of the frame and shafts 16, 17, 18, at the other end. (The fourth shaft is not shown in the drawings.) The shafts mount rolls of a flexible sheet material 19 such as fabric, plastic, thin sheet metal, etc., the material being stretched between the end rolls, forming walls of the enclosure 1. The shafts 12, 13, 14, 15 are provided with bevel gears 22 at the ends, meshing with gears 23, and one of the shafts is also provided with a sprocket 24 connected by a chain 25 with a sprocket 26 on the shaft of a motor 28. The shafts 16, 17, and 18 at the other end of the frame are provided with spiral clock springs 29 which keep the sheet material under tension causing the motor to turn in one or the other direction, it is possible to wind the sheet material on one set of shafts, unwinding from the other, and to reverse the process by reversing the motor rotation. Each sheet consists of sections made of different materials, each section being of one particular material or having a particular finish.

The length of each section corresponds to the length of the frame. It is possible, therefore, by moving the sheets in one or the other direction to bring desired sections of the sheets over the sides of the frame, thereby forming a chamber with desired acoustic or reverberating properties. I have found that by changing the material of the walls of the reverberation chamber it is possible materially to change the quality or character of the sound which is being transmitted by the radio.

The character of the sound or its reverberation is also affected by the volume of the chamber. I provide for this purpose means to vary the volume at will, controlling from a central point both the type of the walls and the volume of the chamber.

For changing the volume of the chamber, rolls 30 are provided at the main frame on shafts 31 bearing against the sheet material. The shafts are connected together by bars 20 and are provided with braces 32, pivotally connected at 33 to levers 34, 35. The latter are pivoted at 36 to the brackets 8, 9 at one end of the frame, the other ends of the levers being connected together by bar 27 with nuts 37 engaging screws 38, 39 having right and left threads and rotated by a motor 40. By energizing the motor for rotation in one or the other direction, it is possible to move the levers together or apart, thereby compressing or releasing the walls.

As an additional arrangement for modifying reverberation properties of the chamber, I provide means to change the relative angular positions of the loud speaker and of the microphone. These instruments are mounted for this purpose on pivots 41, 47 and are operated by small motors 52, 53.

A modified reverberation chamber is shown in Fig. 3. A frame 42 is slidably mounted inside a long tubular enclosure 44, the walls of the enclosure forming walls of the reverberation chamber, having a loud speaker 6 and a microphone 7 on the end walls 45 and 46. The tubular enclosure comprises sections, having different finish of their walls made of different materials. The frame 42 can be moved into any desired section by a motor 48, driving a belt 49, mounted on pulleys 50, 51, the ends of the belt being attached to the frame 42, the return portion of the belt passing through suitable holes in the end walls 45, 46.

My acoustic reverberation or sound conditioning chamber can be used for imparting any desired quality to the sound transmitted by radio as for broadcasting, recording, etc. Thus it is possible to modulate the sound of a musical instrument or orchestra to create an impression that the music is being played in an open space, in a large hall, in a small room, etc.

A single reverberation chamber, however, does not produce entirely satisfactory results for the reason that sounds of different frequency differently respond to the conditioning in a particular acoustic reverberation chamber. It is desirable, therefore, to separate the sound into several bands of different frequency, sending each band through a separate conditioning chamber. Such a system is shown diagrammatically in Fig. 4. It comprises microphones 54 which may be placed in an auditorium, music hall, motion picture studio, or similar places where sound is generated. Electric impulses from the microphones pass through an amplifier 55 into bus bars 56. One portion of the total electric energy of the sound

is transmitted directly through an amplifier 57, line 58, amplifier 59, to the amplifier-mixer 60. The other portion of the sound energy is divided into different frequency bands, passing through amplifiers 61, 62, 63 and through reverberation chambers 66, 67, 68, from which the electric impulses are collected by bus bars 88 and conducted to an amplifier 70 and to the mixer-amplifier 60. Potentiometers 71, 72, 73, 74 are provided to regulate the relative amounts of energy passing through the different branches of the transmission system. Similar potentiometers 75, 76, 77 are provided at the amplifiers 59 and 70, and for the amplifier 60.

Separation of the sound into bands of different frequency may be accomplished mechanically or electrically. Mechanical means consists in the adjustment of the volume of the reverberation chamber whereby the particular chamber becomes responsive to frequencies within a certain range. Adjustable chambers 66, 67, 68 are used for this purpose. They may be so adjusted that their bands somewhat overlap each other so as to avoid blind zones of frequencies.

Bands may be also separated electrically, using band pass filters, 78, 79 with amplifiers 80, 81 and reverberation chambers of constant volume 80, 81.

The control motors 28, 40 of the reverberation chambers are connected by leads 82, 83, 84 with controllers 85, 86. All the potentiometers for the branch lines and the motor control apparatus are placed on a control table where an operator can manipulate them in accordance with the desired final effect. Additional potentiometers 87 may be provided between the microphones and the line 69.

A more or less large number of reverberation chambers or enclosures may be used for radio recording or broadcasting. The chambers 66, 67, 68, 69, also 66', 67', 68', 69' may be connected in groups of a few as shown in Fig. 5, each group containing several chambers. The microphone circuits are connected with potentiometers 92 for regulating relative strength of impulses from the individual chambers. A common potentiometer 94 may be provided for further adjustment of the individual signals before they are passed into amplifiers 95, 96.

A modified acoustic reverberation chamber is shown in Fig. 6 comprising an enclosure 98 provided at the sides with bypass ducts 99 and 100 with shutters 101, 102 which can be adjusted to any desired degree of opening. The bypass ducts can be used to vary the volume of the chamber, and, also to divide the sound waves into several channels of different length thereby adding novel acoustic effects.

In another modification shown in Fig. 7 the enclosure 103 is provided with an additional chamber 104 at the side, having ducts 105 being directly opened into the surrounding space and provided with shutters 106. The open ducts modify the reverberation properties of the chamber. Movable piston-like members 107 may be also provided to vary the volume of the extension chamber.

In combining several acoustic chambers as shown in Fig. 4, the controls can be assembled in one place where an operator can manipulate contact points or switches arranged in the form of a keyboard. A special music or other chart may be provided for guiding the operator.

It will be understood that various features and principles of each of the embodiments of the in-

vention above described or referred to may be utilized or substituted in the other embodiments.

While the invention has been described in detail with respect to certain particular preferred examples, it will be understood by those skilled in the art after understanding the invention, that various changes and further modifications may be made without departing from the spirit and scope of the invention, and it is intended therefore in the appended claims to cover all such changes and modifications.

What is claimed as new and desired to be secured by Letters Patent is:

I claim as my invention:

1. A reverberation modulator comprising an enclosure having a wall made of a flexible material; means to support a loud speaker and a microphone in the enclosure; a remotely controlled motor at the enclosure; means to move said walls by the motor in a transverse direction for varying the volume of the enclosure, and means for passing said flexible wall in a plurality of generally transverse directions to bring the various portions thereof from a gathered position to an operative position as desired.

2. A reverberation modulator comprising a frame; walls movably supported at a plurality of sides of the frame having a series of interchangeable portions of different reverberation properties along their length; a motor at the enclosure; means to move the walls by the motor lengthwise for placing portions of the walls with desired reverberation properties over the frame; and means to support a loud speaker and a microphone in the frame; said moving means serving to interchange portions of said walls to bring one portion out of operative relation with said loud speaker and microphone and to bring another portion into operative relation with said loud speaker and microphone.

3. Means to control reverberation in sound transmission by radio comprising a plurality of reverberation enclosures for loud speakers and microphones, each reverberation enclosure being adapted to reproduce a sound of a limited band of frequency different from the frequencies of the other reverberation enclosures; means to combine the electric impulses from different enclosures into a single channel; and means to modulate the reverberation in different enclosures by varying physical properties of the enclosures.

4. Means to control reverberation in sound transmission by radio comprising means to convert sound into electric impulses; a plurality of enclosures forming reverberation chambers; means to separate from the electric impulses bands of selected frequencies and to direct the bands into the individual reverberation chambers; means to convert the selected bands into sound in the reverberation chambers; means to modulate the sound by varying physical properties of the reverberation chambers; means to convert the modulated sounds into electric impulses; and means to combine the electric impulses from the reverberation chambers with the unmodified electric impulses.

5. Means to control sound transmission comprising a plurality of reverberation enclosures; means to convert a sound into electric impulses of different frequencies; means to selectively reproduce the sounds of different bands of frequency in different reverberation enclosures; electromagnetic means to modulate the sound in the enclosures by varying physical properties of the enclosures; remote control for the electromagnetic

means; means to individually vary the intensity of the electric impulses from different enclosures; means to combine the impulses from the enclosures into groups; means to modulate the impulses from the groups; and means to combine the modulated impulses from the groups into a single channel.

6. A method of modulating sound in radio transmission consisting in dividing sound into bands of different frequencies; reproducing the different frequency bands in different reverberation chambers; modulating the sound in the chambers by varying by remote control reverberation properties of the chambers; converting the sound in the chambers into electric impulses; individually modulating the impulses; and combining the impulses from different chambers into a single channel.

7. A reverberation modulator comprising enclosure means a wall of which has interchangeable portions of different reverberation characteristics, electrosonic means, and means to impart relative movement to said wall and said electrosonic means to bring said electrosonic means and one portion of said wall out of operative relationship and to bring said electrosonic means and another portion of said wall into operative relationship.

8. A reverberation modulator comprising a set of stationary wall portions, a set of movable wall portions, electrosonic conversion means carried by one set, the various portions of the movable set having surfaces of varying sound reflecting

qualities and means to move said movable set to interchange said portions to bring one portion into operative relation with said stationary wall portions and another portion out of operative relation with said stationary wall portions, said chamber having substantially constant volumetric characteristics during said change.

9. A reverberation modulator comprising a set of stationary wall portions, a set of movable wall portions, electrosonic conversion means carried by one set, the various portions of the movable set having surfaces of varying sound reflecting qualities, and power means for effecting accurate and measurable relative adjustment of said wall and said electrosonic means to interchange portions of said wall forming part of said enclosure to bring a portion of said wall out of operative relationship with said conversion means and to bring a wall portion having different reverberation characteristics into operative relationship with said conversion means.

10. A reverberation modulator comprising a set of stationary wall portions, a set of movable wall portions, electrosonic conversion means carried by one set, the various portions of the movable set having surfaces of varying sound reflecting qualities, and remote control means to move said movable set relatively to said stationary set to remove one of the portions of said set and to bring into operative relationship another of the portions of said set.

MAURICE PARISIER.
